(No Model.)

B. TYSON.
AMALGAMATOR.

No. 372,722.

Patented Nov. 8, 1887.

Fig. 1

UNITED STATES PATENT OFFICE.

BRYAN TYSON, OF WASHINGTON, DISTRICT OF COLUMBIA.

AMALGAMATOR.

SPECIFICATION forming part of Letters Patent No. 372,722, dated November 8, 1887.

Application filed October 6, 1883. Serial No. 108,337. (No model.)

To all whom it may concern:

Be it known that I, BRYAN TYSON, a citizen of the United States, residing at Washington, in the District of Columbia, have invented certain new and useful Improvements in Amalgamators, of which the following is a specification, reference therein being had to the accompanying drawings.

In the accompanying drawings, Figure 1 is a top view of my machine. Fig. 2 is a longitudinal sectional view of same on line *xx*. Fig. 3 is a side view of one of the agitators. Fig. 4 is an enlarged sectional view of same.

The object to be attained by this machine is to afford necessary facilities for keeping the sands that overlie quicksilver in properly-constructed receptacles loose, thus affording proper facilities for bringing the precious metals—such as gold and silver—into contact with the quicksilver with which said receptacles have been partially filled. If said precious metals will amalgamate, they will unite with and settle into the quicksilver; if not, they will rest at ease on the top of same.

In the construction of my improved amalgamator a sluice-box, A, of proper dimensions, placed on a suitable incline, is employed. Said sluice-box is preferably provided with niches B and B'.

C and C' are receptacles for holding and working quicksilver, constructed substantially as shown in my patent dated May 18, 1886, No. 342,272, for which no claim is made in this application. Said receptacles should be placed at right angles across the sluice-box, extending into the niches. They should fit sufficiently loose in the niches to admit of their being readily lifted in and out.

A substantial frame of proper dimensions, composed of four upright posts, D D, securely bound together, is constructed. This frame serves as a support for the two pieces E E. From said pieces agitators F F are suspended by means of the rods G H, held in position and adjustable by screws and nuts I. The agitators are preferably brought to a sharp point at each end. Said rods are properly secured to the agitators by means of bolts J K, thus forming flexible joints that permit the agitators to be worked back and forth. The agitators are of suitable length to work inside of the receptacles C and C'. Said receptacles may be of

proper width for one agitator only to work in, as C, or they may be sufficiently wide for any convenient number of agitators to work in—say three, as C'. Any convenient number of receptacles C and C' may be employed, or one kind alone may be used to the exclusion of all others, as may be found best in practice. When constructed for one agitator only, the pattern (grooved riffle) as shown in Patent No. 270,156, dated January 2, 1883, is preferred. The three agitators that work in the receptacle C' may be bound together, so as to be of proper distances apart, by means of blocks L L, placed between the stems that extend from the agitators, and a bolt passed through said blocks and stems. These agitators are preferably constructed of some hard metal, and may be provided with a flange, M, on either side. Said flanges may be brought to a sharp edge, the bevel to effect this being preferably on the top side. Below said flanges thin lugs N, preferably brought to a sharp edge, may be constructed. The bevel to effect this may be the same on the top and bottom sides.

The lugs N may be dispensed with, and in lieu thereof any convenient number of flanges M may be employed, as may be found best in practice.

O is an axle working in proper bearings, provided with a crank, P, preferably at either end, though one crank alone can be made to answer. Said axle is also provided with a wheel, Q, which may be propelled by means of a belt or any other convenient power; but any other device that will produce a gentle sliding motion of the agitators may be employed in lieu of cranks, as may be found best in practice.

R are connecting-rods that connect said cranks with the piece S, which should be properly secured to the agitators F F. When the wheel Q is turned, said agitators will be worked to and fro, thus keeping the sands overlying the quicksilver in said receptacles C C' loose. By this means excellent facilities are afforded for bringing the precious metals into contact with the quicksilver. The bars T T, placed in the receptacle C' and properly secured thereto at each end, will cause the sands overlying the quicksilver in said receptacle to be agitated much more effectually than could be done without them.

The agitators F F should not be run suffi-

ciently fast to throw out the quicksilver in the receptacles C and C'. A slow gentle motion will agitate the sands sufficiently well for all practical purposes. Said agitators should extend to a sufficient depth below the surface of the quicksilver to prevent any sands coming between the bottoms thereof and the quicksilver, thus preventing flouring of same. The quicksilver will not only serve for amalgamating purposes, but will also render important services in giving the sands situated thereon a peculiar agitation, thus facilitating the precipitation of the precious metals. Quicksilver lost from works situated above can be readily precipitated and saved. The surplus quicksilver thus caught in said receptacles can be caused to flow therefrom automatically by means of a device shown in Patent No. 270,156, dated January 2, 1883, Fig. 9. Nothing is claimed for said device in this patent. In this way a uniform quantity of quicksilver can be maintained in said receptacles, even where the amount caught is considerable. This machine will take rusty gold as readily as it will gold that will amalgamate.

Having described my invention, what I claim

as new, and desire to secure by Letters Patent, is—

1. The agitators F F, suspended from pieces E E by means of rods G H, operated by the cranks P P and connecting rods R R, all constructed to move the agitators transversely to a sluice-box, in combination with a sluice-box provided with niches B and B', and receptacles C and C', for holding and working quicksilver, substantially as and for the purposes described. 30

2. The agitators F F, suspended from pieces E E by means of rods G H, operated by the cranks P P and connecting rods R R, in combination with a sluice-box provided with niches B and B', and receptacles C and C', for holding and working quicksilver, with which they are filled to a proper depth, substantially as and for the purposes described. 35

2. The agitators F F, suspended from pieces E E by means of rods G H, operated by the cranks P P and connecting rods R R, in combination with a sluice-box provided with niches B and B', and receptacles C and C', for holding and working quicksilver, with which they are filled to a proper depth, said receptacles being provided with bars T T, substantially as and 40

45 for the purposes described.

In testimony whereof I have affixed my signature in presence of two witnesses.

BRYAN TYSON.
